UNITED STATES PATENT OFFICE

GUY B. BEABOUT, OF ZANESVILLE, OHIO

METHOD AND APPARATUS FOR CLEANING GRAVEL OR THE LIKE

Application filed November 15, 1928. Serial No. 319,558.

This invention relates to a method and apparatus for washing aggregate materials for concrete such as gravel, broken stone or the like.

In order that my invention may be clearly understood, I will point out and describe generally several methods and devices now commonly employed for washing materials of the above character, and then point out wherein my invention differs and obtains results not possible with the devices and methods now usually employed.

The following are well known methods and devices for washing concrete aggregate materials or the like and may be generally described as follows:

(1) Apparatus wherein the material flows downward upon a chute or flume and a strong spray of water is directed upon the material;

(2) Apparatus comprising a revolving drum or the like wherein the material is agitated in the presence of a strong spray of water.

(3) Apparatus comprising a screw conveyor or log washer through which the material is passed and into which water is admitted in large quantities and under pressure.

The methods referred to depend upon agitation of the material in water for the removal of silt and stain, and depend upon a large quantity of water being employed for separating and carrying off all objectionable materials, such as coal, sticks, leaves, etc. These methods usually operate inefficiently for the purpose intended—that is, the stain and silt is not thoroughly removed and the coal, sticks, etc. are not entirely separated from the heavier particles being retrieved.

The machines and devices heretofore described are expensive to manufacture and require a considerable amount of power to operate them. The capacity or amount of material that can be handled by each machine is relatively small. The machines frequently require repair and remain idle a considerable time for such repair. All these disadvantages result in a relatively high operating cost and a relatively poor product.

It may also be here noted that coal washers, jigs, vanning machines and riffle boards as

known to the art are not suitable for washing aggregate materials of the character heretofore defined.

The prime purpose of this invention is to provide a method and apparatus whereby materials of the general character referred to can be rapidly and thoroughly cleaned at a relatively low cost.

Other objects, and objects relating to details of construction, combination and arrangement of parts will hereinafter appear in the detailed description to follow.

In carrying out my invention I provide a suitable apparatus whereby small batches or amounts of material may be individually subjected to a cleansing process in a rapid and efficient manner. The cleansing operation comprises subjecting each small batch of material for a short interval of time to freely flowing clear water in order to cause lighter particles such as silt, sticks, leaves, coal, etc. to separate from the material and travel ahead of the heavier particles—the same as water pushes leaves forwardly thereto when initially flowing in the gutter of a street. The material is subjected to the free flow of clear water a sufficient period to remove all objectionable particles, and also a sufficient period to thoroughly rinse the heavier particles being retrieved. The operation of the apparatus permits time for the cleansed material to dry and when the material is discharged from the apparatus it is in a thoroughly cleansed and marketable condition.

The present invention is illustrated by way of example in the accompanying drawings, in which—

Fig. 1 is a perspective view of an apparatus by which my invention may be practiced.

Fig. 2 is a vertical longitudinal sectional view taken substantially on line 2—2 of Fig. 1.

Fig. 2a is a detail view showing a modified form of a water seal employed in the apparatus shown in Fig. 1.

Fig. 3 is a perspective view of a modified form of apparatus by which my invention may be practiced.

Fig. 4 is a transverse sectional view taken substantially on line 3—3 of Fig. 3.

Fig. 5 is a perspective view of another modified form of an apparatus whereby my invention may be practiced.

Fig. 6 is a longitudinal sectional view taken substantially on line 6—6 of Fig. 5.

Fig. 7 is a transverse sectional view taken substantially on line 7—7 of Fig. 6.

10 Fig. 8 is a perspective view showing a still further modified form by which my invention may be practiced.

Fig. 9 is a longitudinal sectional view taken substantially on line 9—9 of Fig. 8.

15 Referring in detail to the drawings, and particularly to Figures 1 and 2, the numeral 10 indicates, generally, a supporting frame and 11 suitable pedestals secured to said frame. The pedestals or legs 11 may be four 20 in number and each terminates at its upper end in a suitable bearing 12'. The bearings 12' may serve for journaling a pair of shafts 12. Each shaft 12 may have suitably secured thereto a pair of sprocket wheels 13, and 25 about these sprocket wheels there may be trained a pair of sprocket chains 14. One of the shafts 12 may carry a suitable pinion 15 which may be driven through a worm gear 16 carried by a power shaft 17.

30 The sprocket chains 14 have secured thereto a plurality of troughs 18, each of which has its one end closed as at 19, while its other end is open as shown. These troughs are disposed transversely to the direction of travel 35 of the sprocket chains. At the open ends of the troughs there may be arranged a suitable drain as indicated at 20 and this drain may be connected with a suitable drain pipe as at 21. The bottom portion of each trough, adjacent its closed end, is perforated as indicated at 22, and beneath the perforated portion of each trough there is provided an auxiliary bottom 23, which forms a chamber as shown. Each chamber communicates with a 40 pipe 24 which extends upwardly to the upper and rearward edge of the associated trough. The troughs are so mounted that when disposed horizontally they abut each other in close relation and between adjacent 45 troughs there may be provided a suitable rubber strip or the like as indicated at 25 in order to provide a seal against the passage of water between the abutting edges of said troughs.

50 Each trough is further provided, adjacent each end thereof, with a pair of water sealing flanges 26. The associated ends of the flanges 26 are, in each instance, connected by an end wall as shown. These end walls are 55 of such a height that they are flush with the underside of the end portions of headers 27 when flanges 26 pass through said headers. Each pair of flanges has associated therewith a header generally indicated at 27. Each 60 header comprises a hollow casting corre-

sponding in width to the distance between a pair of sealing flanges 26 carried by the troughs. The bottom of each casting is open and its lower edges are provided with opposing inwardly turned flanges which co-operate with the sealing flanges 26 of the troughs for forming a water seal (Fig. 2a). Suitable grease cups 30 may be provided to afford the necessary lubrication for the seals occurring between the header 27 and sealing flanges 26. Each header is connected with a suitable water supply pipe 28 and each pipe 28 may be provided with a suitable regulating valve as shown. Also, each water pipe 30 has extended therefrom an auxiliary water supply pipe 29 which may be provided with a valve as shown. The auxiliary supply pipes 29 are directed so that water flowing therefrom will be sprayed upon material deposited in the troughs 18.

35 A suitable feed chute 31 should be so positioned that material can be deposited upon the perforated portion of the bottom of each trough 18. Suitable means not shown, may be provided to regulate the flow of material 40 from the chute 31 into the troughs 18. The power shaft 17 should be rotated to move the troughs in a clockwise direction, and at one end of the apparatus there should be provided a suitable chute 33 into which the 45 washed material may be deposited and carried to a suitable storage place.

50 In the use of the apparatus shown in Figs. 1 and 2 and heretofore described, the power is applied so that the troughs may move in 55 a clockwise direction at a relatively slow rate of speed, and the material is deposited in said troughs from the chute 31 as they move therebeneath. Water is admitted to the headers 27, and as the sealing flanges 26 of the troughs 18 move into the headers 27, water flows downwardly through the pipes 24 and into the space beneath the troughs provided by the bottoms 23. The water entering beneath the troughs will flow upwardly through the gravel or material deposited in the troughs. Also, water can be admitted from the pipes 29 into said troughs. The upward flow of the water through the material, together with the water provided by the 60 pipes 29, establishes a free flow of water toward the open ends of the troughs. The movement of the water upwardly through the material separates the lighter particles therefrom and also cleanses the material. The 65 lighter particles, together with the silt removed from the material, are pushed ahead of the heavier particles toward the open end of the troughs and may flow into the trough 70 and from thence to a suitable drain as at 21.

75 It should be here noted that the method of cleansing materials as employed by the apparatus heretofore described does not utilize any strong current of water. It is sufficient 80 that water under low pressure enter the bot-

toms of the troughs and buoy upwardly through the material. The water afforded by this entrance to the troughs, together with the water admitted from the pipes 29, is sufficient to cause a free flow of water that will push all light particles ahead of the heavier particles being retrieved.

As the troughs move beneath the headers 27 two or more will have water admitted thereto from said headers. After the troughs have moved beyond the headers there is a period before the same reach dumping position. During this period the material can drain, and when dumped into the chute 33 the material is substantially dry and clean. It is, of course, understood that the apparatus may be made any length desired in order to insure that the material will have sufficient time for drainage after the water 20 stops flowing upwardly therethrough from the headers 27.

It should also be noted that during the latter part of the period when the troughs pass beneath the headers 27 the material in 25 said troughs is being subjected to what may be termed a rinsing process—that is to say, substantially all of the slit and stain, together with light particles, is removed from the material, an appreciable period before 30 the upward flow of water therethrough ceases, and consequently this latter period of water flow serves only for rinsing the material.

In connection with the operation of the apparatus it may be noted that the water 35 entering upwardly through the perforations in the bottoms of the troughs 18 is the most effective for washing the material as compared to the water admitted to said troughs from the pipes 29. The water admitted to 40 the troughs from the pipes 29 assists in the washing of the material in that such additional flow of water furnishes force and volume to help break up and scatter the material so that the upwardly flowing water can be 45 more effective.

Referring to Fig. 2a, I have shown a slightly modified form of water seal which may be used in connection with the headers 27 and the troughs 18. In this modified construction each trough is provided, adjacent each end thereof, with a pair of sealing flanges 34, which are connected by suitable end walls as in Figures 1 and 2. Each flange has its upper and outer edge offset as at 35 and this offset portion is adapted to fit into a similar offset flange 36 carried by the header 27.

Referring to Fig. 3 of the drawings, this modified form of apparatus comprises suitable pedestals 40, which terminate at their upper ends in suitable bearings adapted to journal a shaft 41. The shaft 41 may support, through suitable members extending radially therefrom, a drum 42', said drum 65 being concentric to the shaft 41 and having

formed integrally therewith a plurality of blades 42 adapted to form a number of troughs 43'. These troughs extend substantially the entire length of the shaft as shown, and each trough is provided with a partition 70 43' for the purpose of providing a longitudinal compartment 44. Each division wall 43 has one end portion thereof perforated as indicated at 45. One end of each trough 43 is provided with a closure as shown at 46. 75

Adjacent opposite ends of the troughs there is secured what may be termed a sealing ring 47. Each sealing ring 47 is provided with a plurality of openings 48, one for each of the troughs 43. Each opening 48 communicates with a pipe 49 which extends to the compartment 44 of the associated trough. With each sealing ring 47 there is associated a header 50 which is in the form of a hollow casting having an open bottom, 80 said bottom being provided with suitable flanged edges as indicated at 51, which are adapted to cooperate with the rings 47 and provide a water seal. Also, each header 50 may be provided with a suitable number of grease cups 52 to permit lubrication for the sealing rings 47 and said headers 50. Each header 50 is suitably connected with a water supply pipe 53 and each pipe 53 may be provided with a control valve as shown. 85

The troughs may be rotated through the medium of a rack gear 55 driven from a pinion 56 carried by a power shaft as shown. A chute 57 may be provided whereby the material to be cleaned may be deposited in the 100 uppermost troughs as the same are beneath the chute 57 with the rotation thereof. A chute 58 can be arranged to receive the cleaned materials discharged from the troughs when said troughs reach a discharging position, and at 59 there is shown a trough positioned to receive the refuse and water escaping from the open ends of the troughs 43. 105

The device shown in Figs. 3 and 4 and heretofore described operates upon the same principle as that shown in Figs. 1 and 2. In the apparatus shown in Figs. 3 and 4, the material is discharged from chute 57 into the troughs 43, while said troughs are slowly rotated. Water enters upwardly through the troughs from the headers 50 and also water is admitted to said troughs from the pipe 50'. Water entering through the perforations in the troughs buoys the material upwardly and removes the silt and stain, together with all light particles. The silt and lighter particles are pushed ahead of the heavier particles and permitted to leave the trough at its open end. The water entering the troughs from the pipe 50' serves to scatter the material being treated and permits more effective cleansing in the manner heretofore pointed out. 115

Referring to Figs. 5, 6, and 7, there is 120

shown a drum generally indicated by the reference numeral 60 which may be supported at each end by a riding ring 61. These riding rings may be supported to permit rotation of the drum in any conventional and desired manner. The drum at one end may carry a rack 62 which may be engaged by a pinion 63 carried on one end of a suitable power shaft 64. Within the drum there is mounted a number of spiral-shaped vanes 65. In the present case I have shown four such vanes, which are secured to the inner periphery of the drum 60 and so arranged at the feed end of the drum that a chute 66 may be used to deposit a batch of material into each trough provided by the vanes 65 with each complete rotation of the drum. For each convolution of a vane the drum is provided with a slot such as indicated at 67. Such slots are provided for each of the vanes, and the slots for each vane are aligned longitudinally of the drum.

Along one side of the drum there is arranged a water supply pipe 68 which may be provided with a control valve 69 and which has a plurality of outlets 70 arranged to register with the different slots 67 as the drum is rotated. There is also provided a water supply pipe 71 which extends centrally and longitudinally of the drum 60 and is provided with a suitable regulating valve as shown. This pipe is preferably provided with two sets of orifices arranged longitudinally thereof as illustrated to advantage in Figs. 6 and 7. Beneath the drum there may be arranged a trough 72 for the purpose of carrying off water and refuse and at one end of the drum there is arranged a suitable material discharge chute 73.

In the operation of the apparatus shown in Figs. 5 to 7, inclusive, and heretofore described, the drum 60 is rotated at a suitable speed and gravel or other material fed into the different troughs or grooves provided by the vanes 65 from the chute 66. Referring to Fig. 7, if the drum is rotated in the direction of the arrow 74 the gravel will slide in the groove provided by the vane 65 and maintain the position shown. As the gravel comes into register with a slot 67, water will flow upwardly and the gravel and the silt will be washed therefrom. The water will flow forwardly through the gravel and push the silt and other lighter particles ahead thereof and discharge the same through the succeeding slot 67 when said slot reaches a position illustrated in Fig. 7. The refuse passing from the slots 67 flows into the drain 72. It should be noted that the gravel or other material will always maintain the position illustrated in Fig. 7 and will not escape through the slots 67. It will also be noted that adjacent the discharge end of the drum 60 no water is admitted through the slots 67 and thereby the material is given time to

drain before being discharged into the chute 73.

Referring to Figs. 8 and 9, the apparatus shown comprises a casing generally indicated by the reference character 76, which may be open at its top as shown. Within the casing there may be suitably supported a pair of shafts 77, one adjacent each end thereof. Each shaft may carry a pair of sprocket wheels 78 and about these sprocket wheels there is trained a pair of sprocket chains 79, which have secured thereto a multiplicity of blades 80. The blades 80 extend the entire width of the casing 76 and when moving over the bottom of the casing provide troughs 81.

One side of the casing or housing 76 is cut away as at 82 and consequently the troughs 81 formed by the blades 80 with the bottom of the casing are open at one end. Adjacent the closed end of the troughs the bottom is provided with a perforated section 84 which communicates with a compartment 85 formed there-beneath, preferably as shown. This compartment has extended therein a pipe 87 which terminates within the compartment in a plurality of nozzles 88. The pipe 87 may be connected to a suitable water supply and provided with a valve as shown for controlling the flow of water into the compartment 85. Also, a water supply pipe 89 may be arranged within the casing and provided with nozzles 90 for admitting water into the troughs 81. The pipe 89 may have a suitable control valve as shown.

At a point above the casing 76 there is arranged a feed chute 91 whereby material may be discharged into the troughs 81 formed by the blades 80 when passing over the bottom of the casing 76. A supplemental chute 92 may be provided to insure that the material will be discharged into the troughs 81. The casing 76 may also be provided with a recess 93 at its one end to permit the washed material to be discharged into a suitable chute 94.

One of the shafts 77 may carry a drive sprocket 95 about which there may be trained a suitable sprocket chain 96 which may be driven from a suitable source of power.

In operating the apparatus shown in Figs. 8 and 9, the material is discharged into the troughs 81 provided by the blades 80 and as the material passes over the perforated section 84 water passes upwardly therethrough. Also, water is admitted from the pipe 89 to the troughs 81. The water passing upwardly through the material, together with the water admitted from pipe 89 cleanses the material and separates the lighter particles from the heavier in the same manner as described for the apparatus shown in Figs. 1 and 2—that is, the silt removed from the material together with the lighter particles such as leaves, etc., is pushed forward from the heavier particles and permitted to discharge from the open ends of the troughs. When the ma-

terial passes beyond the perforated section 84 of the bottom of the casing 76 the same is permitted to drain prior to the time it is discharged into the chute 94. The bottom of the casing 76 may be suitably perforated substantially its entire length to facilitate the draining of the material after passing the perforated bottom portion 84. While I have described the structural details of the different forms of apparatus by which my invention 10 may be practiced, I do not intend to so limit my invention as indicated by the appended claims.

I claim:

1. A method for washing and cleansing gravel or the like which comprises separating the gravel into relatively small batches, maintaining the batches of gravel in a settled and unagitated state, causing water at 15 relatively low pressure to flow upwardly through each batch of gravel and at the same time permitting the water rising through the gravel to flow freely away therefrom whereby all objectionable matter washed from the 20 gravel, together with all light particles separated therefrom by the water will be pushed away from the gravel by the water when flowing in its last mentioned course.

2. A method for washing and cleansing gravel or the like which comprises separating the gravel into relatively small batches, maintaining the batches of gravel in a settled and unagitated state causing water at 25 relatively low pressure to flow upwardly through each batch of gravel and also downwardly thereon, and at the same time permitting the water rising through the gravel, as well as the water flowing downwardly thereon to flow freely away from the gravel whereby 30 all objectionable matter washed from the gravel together with light particles separated therefrom will be pushed away from the gravel by the water when flowing in its last mentioned course.

3. In a material washing apparatus of the character described, a plurality of material receiving troughs each having its one end open and a portion of its bottom adjacent its closed end perforated, means whereby 35 the troughs may be supported in a horizontal plane and moved from a material-receiving position to a dumping position, means whereby a batch of material may be deposited in each trough upon said perforated portion when the trough is brought to its receiving position, and means whereby water may be caused to flow freely upwardly 40 through each batch of material while said troughs are moving from receiving position 45 to dumping position.

4. In a material washing apparatus of the character described, a plurality of material receiving troughs each having its one end open and a portion of its bottom adjacent its closed end perforated, means whereby the

troughs may be supported in a horizontal plane and moved from a material-receiving position to a dumping position, means whereby a batch of material may be deposited in each trough upon said perforated portion when the trough is brought to its receiving position, and means whereby water may be caused to flow upwardly through the batch of material in each trough a predetermined period prior to said trough reaching its dumping position and thereby permit a predetermined interval for draining the material through the perforated bottoms of the troughs.

5. A material washing apparatus of the character described comprising a rotary drum having trough-like receptacles extending longitudinally thereof with one end open and the bottom of each receptacle perforated adjacent its closed end, means for rotating the drum whereby the troughs may be brought to a receiving position and a dumping position, means for depositing a relatively small batch of material in each trough and upon its perforated portion when said trough is brought to its receiving position, and means for causing water to flow upwardly through said material a predetermined period while said trough is moving from its receiving position to its dumping position.

6. A material washing apparatus of the character described comprising a rotary drum having trough-like receptacles extending longitudinally thereof with one end open and the bottom of each trough perforated adjacent its closed end, means for rotating the drum whereby the troughs may be brought to a receiving position and a dumping position, means for depositing a relatively small batch of material in each trough upon its perforated portion when said trough is brought to its receiving position, and means for causing water to flow upwardly through the perforations in the bottom of each trough for a predetermined period immediately after such trough receives a deposit of material, the flow of said water being stopped a predetermined period prior to the time each trough reaches its dumping position to permit draining of said material.

7. In a material washing apparatus of the character described, a plurality of material receiving troughs, each trough being adapted to permit water to flow upwardly through its bottom and out an end thereof, means for successively depositing a relatively small batch of material into said troughs and means for causing water at a low pressure to flow upwardly through the bottom of each trough and the batch of material therein.

8. In a material washing apparatus of the character described, a plurality of material receiving troughs, each adapted to permit

water to flow upwardly through its bottom and out an end thereof, means for successively depositing a relatively small batch of material in said troughs, means for causing water at a low pressure to flow upwardly through each batch of material deposited in said troughs, and means for permitting water to flow downwardly upon each batch of material during the period water is flowing upwardly therethrough.

9. In a material washing apparatus of the character described, a plurality of material receiving troughs, each trough being adapted to permit water to flow upwardly through its bottom and out an end thereof, means whereby the troughs may be supported in a horizontal plane and moved from a material receiving position to a dumping position, means whereby a batch of material may be deposited in each trough when brought to its material receiving position, and means whereby water may be caused to flow upwardly through the batch of material in each trough while said troughs are moving from receiving position to dumping position.

In testimony whereof I affix my signature.
GUY B. BEBOUT.
